His Attorney.

UNITED STATES PATENT OFFICE

2,481,985

HIGH REACTANCE TRANSFORMER

Charles E. Derbyshire, Fort Wayne, Ind., assignor
to General Electric Company, a corporation of
New York

Application January 15, 1949, Serial No. 71,955

2 Claims. (Cl. 171—119)

1

This invention relates to an electric induction device and more particularly to the construction of a magnetic core for a high reactance transformer.

It is desirable to incorporate, in many electrical circuits, specific values of reactance and if a transformer is present in the circuit this reactance may be achieved by utilizing a transformer of the high reactance type. Thus, for example, in circuits having electron discharge devices, the reactance of a transformer may be used to limit the circuit current after conduction through the discharge device has begun.

This invention provides a new and simple construction of a magnetic core for a high reactance transformer device. On the central leg of a magnetic core constructed of stacked E and I shaped laminations are concentrically wound primary and secondary transformer coils which are separated from one another by magnetic shunt members located outside of the windows of the main core and which lie in a plane different from that of the plane established by the legs of the main core members. The magnetic shunt members provide a low reluctance flux leakage path so that a portion of the flux induced by the primary coil does not link the primary and secondary coils of the transformer together.

It is an object of this invention to provide a new and simple high reactance transformer core construction having magnetic shunt members which lie in a plane different from the plane established by the main members of the core.

It is a further object of this invention to provide a high reactance transformer core construction having an overall length which is less than the length of similar devices in current use.

It is still another object of this invention to provide a new and simple high reactance transformer core construction which is economical to manufacture and is simple to assemble.

The invention will be better understood from the following description taken in connection with the accompanying drawing and its scope will be pointed out in the appended claims.

In the drawing, the figure shown is a partly broken away perspective view of a particular embodiment of this invention as applied to the construction of a core for a high reactance transformer.

Referring now to the drawing, there is shown therein, by way of example, a high reactance transformer device 1 having a magnetic core 2 constructed of stacked E and I shaped laminations 3 and 4. Mounted on the center core leg

2

5, or the center leg of the E shaped laminations, are concentric primary and secondary coils 6 and 7. In order to achieve a high reactance, a certain portion of the flux produced by current 15 flowing through the primary winding 6 is bypassed through magnetic shunts 8, thus decreasing the amount of flux linking the secondary winding 7. It can be seen in the drawing that the magnetic shunt paths 8 may be constructed of L shaped laminations having the foot of contiguous L's alternately mounted at either end of the core. The shunts 8 may be constructed also of U or I shaped pieces of magnetic material, depending upon the characteristics desired. In the drawing, 20 two shunt paths 8 are shown. It is not necessary to limit the construction of this high reactance transformer core to a plurality of shunt paths since one shunt path may be used, again depending upon the characteristics desired.

25 This construction differs from the conventional high reactance transformer core construction in that the shunt paths 8, which are located between the concentrically wound primary and secondary coils 6 and 7, are not in the plane established by the legs of the core but rather in a plane outside of the windows 9 of the core 2. It can be seen, therefore, that the overall length of the core 2 is no greater than that of a standard transformer having a core constructed of E and I shaped 30 laminations. The core 2 may be secured as a unit by any conventional means and in the drawing the bolts 10 and the angle bars 11 are shown. The shunts 8 may be held in place by filling the space between the coil 7 and the shunts 8 with kraft board pieces 12 and wedging them in place. The gap between the shunts 8 and the core 2 may be maintained by definite thicknesses of insulating material 13.

35 While there has been shown and described a particular embodiment of this invention, it will be obvious to those skilled in the art that various changes and modifications can be made therein without departing from the invention and, therefore, it is aimed in the appended claims to cover all such changes and modifications as fall within the true spirit and scope of the invention.

40 What I claim as new and desire to secure by Letters Patent of the United States is:

45 1. A high reactance transformer comprising, 50 in combination, a low reluctance magnetic core constructed of a plurality of stacked E and I shaped laminations, said core having three legs and two windows separating said legs, clamping means cooperating with said core so as to hold said laminations in fixed relationship to one

another, a primary coil mounted on the central leg of said core, a secondary coil mounted on said central leg and concentric with said primary coil, at least one magnetic shunt member constructed of a plurality of stacked laminations, 5 said shunt member located between said concentric primary and secondary coils and separating said coils one from the other, said shunt member providing a low reluctance flux path so that a portion of the magnetic flux induced by said primary passes through said shunt member and does not link said primary and said secondary coils together, said shunt member lying in a plane different from the plane established by said legs of said core and lying outside said windows of said core.

2. A high reactance transformer comprising, in combination, a low reluctance magnetic core constructed of a plurality of stacked E and I shaped laminations, clamping means cooperating with said core so as to hold said laminations in fixed relationship to one another, a primary

coil mounted on the central leg of said core, a secondary coil mounted on said central leg and concentric with said primary coil, magnetic shunt members constructed of a plurality of stacked L shaped laminations having the foot of contiguous L laminations alternately oriented at opposite ends of the body of said L shaped laminations, said shunt members located between said concentric primary and secondary coils and separating said coils one from the other, said shunt members providing a low reluctance flux path so that a portion of the flux induced in said primary coil passes through said shunt members and does not link said primary and said secondary coils together, said shunt members being parallel to and secured on opposite sides of said central leg of said core and lying in a plane perpendicular to the plane established by said legs of said core.
